(57) **CLAIM**

The ornamental design for “companion escutcheons,” as
shown and described.

DESCRIPTION

FIG. 1 is a top front right side perspective view of the com-
panion escutcheons showing our new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a top plan view thereof;

FIG. 7 is a top front right side perspective view of a second
embodiment of the companion escutcheons showing our new
design;

FIG. 8 is a front elevational view thereof;

FIG. 9 is a left side elevational view thereof;

FIG. 10 is a right side elevational view thereof;

FIG. 11 is a bottom plan view thereof;

FIG. 12 is a top plan view thereof;

FIG. 13 is a top front right side perspective view of a third
embodiment of the companion escutcheons showing our new
design;

FIG. 14 is a front elevational view thereof;

FIG. 15 is a left side elevational view thereof;

FIG. 16 is a right side elevational view thereof;

FIG. 17 is a bottom plan view thereof; and,

FIG. 18 is a top plan view thereof.
